UNITED STATES PATENT OFFICE

170,559

POLISHING MACHINE

James Lee Thompson, North Little Rock, Ark.

Application October 14, 1952, Serial No. 21,824

Term of patent 14 years

(Cl. D9—2)

To all whom it may concern:

Be it known that I, James Lee Thompson, a citizen of the United States, residing in North Little Rock, Pulaski County, Arkansas, have invented a new, original, and ornamental Design for a Polishing Machine, of which the following is a specification, reference being had to the accompanying drawing, forming a part thereof.

Figure 1 is a perspective view of the polishing machine from the front and slightly to one side, showing my new design.

Figure 2 is a perspective view from one side thereof.

Figure 3 is a view from above to reduced scale.

The dominant features of my design reside in the portions shown in full lines.

I claim:

The ornamental design for a polishing machine, as shown and described.

JAMES LEE THOMPSON.
